REGULATOR

Andrew Baxter Leven, Brisbane, Australia

Application June 17, 1933, Serial No. 676,372
In Australia June 17, 1932

1 Claim. (Cl. 292—267)

This invention relates to devices, known as openers, stays, or holders, for use in opening casements, windows, fanlights, and the like, and for securing them in the open or closed position.

5 The device covered by this invention is such that the casements or the like may be opened and closed with little effort on the part of the operator and then securely held in any desired position. The device may be arranged to operate 10 left or right handed, and for the operation of pivot hung windows it may be applied to any type whether side pivot hung, center or out of center vertical pivot hung, and so on.

The invention consists of a guide with a rack 15 formed thereon, a carrier slidably carried thereon, a locking block rotatably carried thereby and having teeth thereon which can be caused to engage with the teeth of the rack, and a finger piece on the locking block. An arm or stay, articulated 20 at one end to the carrier, is provided with a pivoted pin and base at the other end. According to the type of window, the guide and rack are secured to the sash or window frame, as the case may be, and the pivoted pin on the arm or stay 25 is secured on the frame or sash.

In order that the invention may be better understood it will now be more fully described with the aid of the accompanying drawing, in which

30 Fig. 1 is a perspective view of one form of the invention;

Fig. 2 is a transverse sectional elevation;

Fig. 3 is a front view;

Fig. 4 is a top plan view of the rack engaging surface of the locking block.

The invention consists of a guide A formed with a rack B on its face. On this guide a carrier C is slidably carried and it in turn carries a locking block D capable of rotation and having 40 teeth D¹ on one face. These teeth D¹, which are preferably substantially inverted V shape, normally engage the teeth 10 (preferably V or diamond shape) of the rack B, as in Figs. 1, 2, 3, and 4, but they may be rotated out of engagement, as in broken lines in Figure 2. The locking block D is provided with and actuated by a finger piece E.

The stay F is articulated to the carrier C and to a base or standard G which is secured to any 50 suitable support.

Generally speaking, the device will be used with

the guide A and rack B with attendant parts on the sash or window, as the case may be, but it will be readily understood that there are cases, such as in the case of fanlights and such like, where it would be more advisable to place the 5 guide A and rack B with attendant parts on the frame.

The device would be made of any suitable metal and the details of construction and the shapes of the various parts could be varied as 10 desired so long as the essential features of the invention are retained.

The operation of the invention is as follows:— To open the casement, window or fanlight, as the case may be, the finger piece E is raised as shown 15 in broken lines in Fig. 2. The teeth on the locking block D being thereby freed from the teeth 10 of the rack B, the block D can be slid along on the guide A causing the stay F to push open the casement or the like. The finger piece E is 20 then turned to the full line position and the locking piece locked with the rack B.

As the teeth D¹ of the block D are of inverted V-shape they engage the diamond shaped teeth 10 of the rack B with a cam or wedging action 25 that insures a tight and non-rattling fit without requiring a strong effort on the part of the operator.

Having now particularly described and ascertained the nature of my said invention and in 30 what manner the same is to be performed, I declare that what I claim is:—

A device of the class described, comprising an elongated guide, a rack formed on said guide, the teeth of said rack being diamond-shaped 35 in plan to provide diverging wedge surfaces on the portions of said teeth extending at right angles to said guide, a carrier slidably mounted on said guide, a rotatable locking block carried by said carrier, said block having an arcuate 40 surface with its axis parallel to said rack, substantially V-shaped teeth formed on said surface of said block, said teeth being engageable with said wedge surfaces of a selected rack tooth whereby to wedge the latter between said teeth 45 on said lock and frictionally maintain said block in a rack tooth engaging position, and said block being rotatable on its aforesaid axis to withdraw its teeth from engagement with said rack tooth to permit said block to be slid along said guide. 50

ANDREW BAXTER LEVEN.
